REINFORCING ROD SPACER

Edgar W. Byars and William B. Allen, Tampa,
Fla.; said Allen assignor to said Byars

Application February 28, 1947, Serial No. 731,598

8 Claims. (Cl. 72—122)

1

This invention relates to reinforce chairs or supports.

The main objects of this invention are:

First, to provide a reinforce chair or support which is well adapted for use on foundations such for example as the bottoms of trenches or earth foundation surfaces for highways or floor slabs or the like.

Second, to provide a support which may be very economically produced and easily installed and which effectively supports the reinforce material on a foundation that is not, in itself, especially compacted.

Third, to provide a reinforce support or chair which includes an effective thrust plate to facilitate positioning of the reinforce seat relative to the foundation and to receive the thrust load upon the reinforce elements.

Fourth, to provide a structure of this character in which the supporting plate can be collapsed or swung to a position to permit compact arrangement of the reinforce chairs or for shipment or storage.

Objects relating to details and economies of the invention will appear from the description to follow. The invention is defined and pointed out in the claims.

Preferred embodiments of the invention are illustrated in the accompanying drawing, in which:

Fig. 1 is an elevational view of a reinforce chair embodying the invention with the chair shown in operative relation to a trench adapted to receive a foundation and with rod-like reinforce elements shown in section.

Fig. 2 is a fragmentary plan view of the structure shown in Fig. 1.

Fig. 3 is a fragmentary perspective view illustrating details of the structure.

Fig. 4 is a perspective view of a modified form or embodiment of the invention.

Fig. 5 is a perspective view of another embodiment of the invention.

In the accompanying drawing 1 represents the ground and 2 a trench formed therein such for example as might be provided for receiving the foundation of a house or like building.

The reinforce support or chair of the invention as embodied in Figs. 1, 2 and 3 comprises a pair of upwardly facing laterally spaced U-shaped seats 3 adapted to receive reinforcing bars or rods 4. The seats 3 are provided with inner legs 5 which are connected by the cross member 6 and outer legs 7 which extend substantially below the cross member 6 for penetrative engagement

with the ground or foundation on which the slab is to be laid. The legs are joined to the seats by downwardly facing U-shaped loops 8. These chairs or supports are formed of heavy gauge wire or rod of suitable gauge depending on the size of the chair and the load which it is designed to carry.

To position the chairs relative to the foundation surface and to support the load on the chairs, 10 we provide a thrust plate 9 in the embodiment shown in Figs. 1, 2 and 3, this thrust plate being provided with pivot tongues or ears 10 struck up therefrom to pivotally engage the cross member 6. The member 6 horizontally offset from the inner legs 5 provides a shaft-like bearing member about which the thrust plate is tiltable and the axis of tilting movement of the thrust plate coincides with the longitudinal axis of the member 6.

15 The plates 9 are desirably formed of sheet metal and to strengthen the same are provided with diagonal ribs 11. This pivotal mounting permits the plate to conform to an uneven surface on the foundation and also to swing into substantially parallel relation to the legs for storage or shipment.

In the embodiment of the invention shown in Fig. 4 the outer legs 12 corresponding to the legs 7 have inward horizontal offsets 13 forming supporting shoulders for the thrust plate 14. In this case the thrust plate is provided with holes 15 receiving the legs and with a longitudinal groove 16 stiffening the plate longitudinally and also providing an effective pivotal engagement of the plate about the horizontal offsets 13 of the legs 12. It will be appreciated that in this structure the plates would normally be packed or shipped in disassembled relation and they can be readily slipped onto the legs. It will also be readily appreciated that any looseness of the legs 12 in the openings 15 of the thrust plate such as permits the thrust plate to be readily slipped onto the legs 12, as above described, will also permit the above described pivotal engagement of the thrust plate with the horizontal offsets 13 of the legs; the thrust plate being relatively thin, any very slight looseness of the legs 12 in the openings 15 will permit a considerable tilting movement. The plate is in thrust engagement with the cross member 6.

In the modification or embodiment shown in Fig. 5 the legs 17 corresponding to the legs 7 and 12 have outward offsets 18 with which the ears 10 of the thrust plate 9 engage. This illustrates an adaptation of the invention for a single sup-

port. The plate 9 is tilttable about the horizontal offsets 18 of the legs 17.

The supports of the invention are highly practical for a wide variety of uses and especially desirable for use on earth foundations as distinguished from concrete foundations although they may be used on concrete foundations if positioned before the concrete or the concrete foundation has set—that is, if positioned while the foundation penetrating legs may be inserted. The thrust plates are mainly desirable in that case in properly positioning the seats relative to the surface of the concrete foundation. Ordinarily, after the concrete foundation has set the legs would serve as sufficient support. However, it is desired to point out that frequently workmen stand or walk upon the reinforce elements so that the thrust plates are highly desirable for sustaining the load.

We have illustrated and described the invention in certain embodiments thereof which we believe will enable those skilled in the art to which our invention relates to embody or adapt the same as may be desired.

Having thus described our invention, what we claim as new and desire to secure by Letters Patent, is:

1. A reinforce support comprising laterally spaced upwardly facing U-shaped reinforce seats each having legs joined thereto on the opposite sides thereof by downwardly facing loops providing inner legs between the seats and providing outer legs on the outer sides of the seats, the inner legs being connected by an integral cross member, the outer legs being extended below the inner legs for penetrative engagement with a foundation, and a foundation engaging thrust plate of sheet metal having tongues struck therefrom pivotally engaging said integral cross member, said thrust member having diagonally disposed reinforcing ribs.

2. A reinforce support comprising laterally spaced upwardly facing U-shaped reinforce seats each having legs joined thereto on the opposite sides thereof by downwardly facing loops providing inner legs between the seats and providing outer legs on the outer sides of the seats, the inner legs being connected by an integral cross member, the outer legs being extended below the inner legs for penetrative engagement with a foundation, and a foundation engaging thrust plate engaging said integral cross member, said thrust plate having means spaced longitudinally of the cross member and surrounding the cross member above the same for pivotally connecting the thrust plate to the cross member, said cross member providing a shaft-like bearing member about which said thrust plate is tilttable, the axis of tilting movement of said thrust plate coinciding with the longitudinal axis of said cross member in the portions thereof surrounded by said means.

3. A reinforce support formed of rod stock and comprising laterally spaced upwardly facing U-shaped reinforce seats, each seat having inner and outer legs joined thereto by downwardly facing U-shaped bends, the inner legs being integrally connected by a horizontal member, the outer legs being extended below said horizontal member for penetrative engagement with a foundation, and a thrust plate engaged with the said horizontal member of said inner legs, said thrust plate having integral tongues extending upwardly and around said horizontal member and spaced longitudinally thereof to pivotally

connect said thrust plate to said horizontal member, said horizontal member providing a shaft-like bearing member about which said thrust plate is tilttable, the axis of tilting movement of said thrust plate coinciding with the longitudinal axis of said horizontal member in the portions thereof surrounded by said tongues.

4. A reinforce support formed of rod stock and conformed to provide an upwardly facing reinforce seat, and legs joined to said seat by downwardly facing loops and adapted for penetrative engagement with a foundation, the legs having horizontal offsets therein, and a thrust plate having openings therethrough through which said legs project, said horizontal offsets being in supporting engagement with said thrust plate and providing shaft-like bearing members about which said thrust plate is tilttable, the axis of tilting movement of said thrust plate coinciding generally with the longitudinal axes of said horizontal offsets.

5. A reinforce support comprising laterally spaced upwardly facing U-shaped reinforce seats each having legs joined thereto on the opposite sides thereof by downwardly facing loops providing inner legs between the seats and providing outer legs on the outer sides of the seats, the inner legs being connected by an integral cross member, the outer legs having offsets therein aligned with said cross member, and a thrust plate perforated to receive said legs and provided with an upwardly facing longitudinal groove receiving the said cross member of said legs and said offsets, said offsets and cross member providing shaft-like bearing members about which said thrust plate is tilttable, the axis of tilting movement of said thrust plate coinciding generally with the longitudinal axes of said offsets and cross member.

6. A reinforce support comprising laterally spaced upwardly facing U-shaped reinforce seats each having legs joined thereto on the opposite sides thereof by downwardly facing loops providing inner legs between the seats and providing outer legs on the outer sides of the seats, the inner legs being connected by an integral cross member, the outer legs having offsets therein aligned with said cross member, and a thrust plate perforated to receive said legs and in thrust engagement with the said cross member of said legs and said offsets, said offsets and cross member providing shaft-like bearing members about which said thrust plate is tilttable, the axis of tilting movement of said thrust plate coinciding generally with the longitudinal axes of said offsets and cross member.

7. A reinforce support formed of a rod comprising an upwardly facing reinforce seat, and legs joined to the seat by downwardly open U-shaped bends, and adapted for penetrative engagement with a foundation, the legs having horizontal offsets therein, and a thrust plate having pivot ears engaging said offsets, said horizontal offsets providing shaft-like bearing members about which said thrust plate is tilttable, the axis of tilting movement of said thrust plate coinciding generally with the longitudinal axes of said horizontal offsets.

8. In a reinforce support, an upwardly facing U-shaped reinforce seat having legs on the opposite sides thereof and joined thereto by downwardly open U-shaped bends, one of said legs having a vertical portion for penetrative engagement with a foundation, the other of said legs having a horizontal offset portion, said vertical

portion of the first mentioned leg extending a substantial distance below the level of the horizontal portion of said other leg, and a thrust plate tilttable about said horizontal offset portion and in thrust engagement therewith and acting to space the reinforce seat from the upper surface of a foundation when the first mentioned leg is in penetrative engagement with a foundation, said seat and legs being formed of a rod-like member bent to shape, said horizontal offset portion providing a shaft-like bearing member about which said thrust plate is tilttable, the axis of tilting movement of said thrust plate coincid-

ing generally with the longitudinal axis of said horizontal offset portion.
